UNITED STATES PATENT OFFICE.

LINCOLN MOSS, OF NEW YORK, N. Y., ASSIGNOR TO ROBINS CONVEYING BELT COMPANY, OF NEW YORK, N. Y., A CORPORATION OF NEW JERSEY.

TRIPPER OR DELIVERER FOR CONVEYING APPARATUS.

No. 863,202.

Specification of Letters Patent.

Patented Aug. 13, 1907.

Application filed November 23, 1903, Serial No. 182,283.

To all whom it may concern:

Be it known that I, LINCOLN Moss, a citizen of the United States, and a resident of the borough of Manhattan, city, county, and State of New York, have 5 invented certain new and useful Improvements in Trippers or Deliverers for Conveying Apparatus, of which the following is a specification accompanied by drawings.

This invention relates to conveying apparatus, but 10 more particularly to the tripper or deliverer for such apparatus. Its objects are to improve upon the construction of tripper for conveyers, to secure greater efficiency thereof, and especially to provide a form of tripper by means of which the material, discharged 15 therefrom can be delivered at a greater distance from the conveying apparatus and from the tripper itself, and thus material can be distributed over a greater area with a single conveyer and a single tripper, than has been possible with the forms of deliverers for conveying apparatus devised heretofore.

The travel of a tripper is always along the line of the conveyer, and is, therefore, in a relatively straight line. So far as I am aware, the delivery from all 20 trippers now in use is either directly from the tripper, or through chutes so arranged that the material discharges therefrom by gravity. It is impossible for such trippers to distribute the material to any considerable distance from the line of their travel, so that it is necessary to make use of a plurality of trippers and a 25 plurality of conveyers, or to change the line of travel of the single tripper, in order to distribute material over a space of any considerable width. It is frequently necessary, for one reason or another, to distribute material over a large area, and it is manifestly desirable 30 to accomplish this with a single conveyer and its tripper, and without moving the conveyer so as to change the line of travel of the tripper.

A further reason for delivering material from a tripper at a distance therefrom, and hence from the conveyer, 35 is that it has been found in practice that the material discharged from the trippers now in use is delivered and piles up so close to the conveyer as often to interfere with its operation and that of the tripper.

My improved tripper is adapted to accomplish the 40 foregoing desirable objects, and to overcome the defects which have been pointed out herein as existing in the trippers which have been devised heretofore.

Further objects of my invention will appear hereinafter, and to these ends the invention consists of apparatus for carrying out the above objects, which 45 apparatus embodies the features of construction, com-

binations of elements, and arrangement of parts, having the general mode of operation substantially as hereinafter fully described and claimed in this specification and shown in the accompanying drawings, in 55 which

Figure 1 is a front end elevation, partly in section, of apparatus embodying the invention; Fig. 2 is a top plan view of the apparatus, partly in section, with some parts omitted; Fig. 3 is a side elevation of the 60 apparatus on a smaller scale; Fig. 4 is a sectional detail view on the line x-x of Fig. 1; Fig. 5 is a detail plan view, showing the gear drives for the side conveyers and the manner in which those conveyers are universally pivoted at their inner, tail, or receiving ends; 65 Fig. 6 is a front end elevation, of a form of the invention in which a single conveyer and a counterweight therefor are rigidly mounted on the tripper or deliverer; Fig. 7 is a front end elevation, and Fig. 8 is a side elevation, both on a smaller scale, of a form of the 70 invention in which a traveling tower furnishes support for the discharge hopper and chutes and the outer ends of the side conveyers.

Referring to Figs. 1 to 6, inclusive, of the drawings, A represents a tripper or deliverer, supported on wheels 75 B, which travel on rails C. The tripper is supplied with coal, ore, or other material, by belt D (only a portion of which is shown). This belt passes over bend pulleys E and F, and forms an ogee curve, like the letter S, over these pulleys. The material carried by 80 the belt, which travels in the direction indicated by the arrow (Fig. 3), is discharged from the belt in line therewith as it passes over pulley F, and falls into the mouth of hopper G, which is rigidly supported and carried on the frame of the tripper.

As shown in Figs. 1, 2, 3 and 7, hopper G is provided with four discharge chutes, I, J, K and L, two of which, I and J, discharge upon the respective side or wing conveyers M and N, while the other two, K and L, afford direct discharges from hopper G to the storage 90 pile or other place in which it is desired to deposit the material.

The inner, tail or receiving ends of side conveyers M and N are universally pivoted on the lower part of the tripper frame, and the outer ends of these conveyers are supported by guys O, the upper ends of which are secured near the top of the tripper frame and a considerable distance apart. Each guy is provided with a turnbuckle P, and by tightening or loosening one or both of the turnbuckles on the guys of either 95 conveyer, as required, the outer or discharge end of that conveyer may be raised or lowered, or swung to

the right or left in a horizontal plane. By raising or lowering the discharge ends of these side conveyers the trajectories of the material discharged therefrom may be varied to a considerable extent, while by 5 swinging these conveyers in a horizontal plane it becomes possible to reach desired points of discharge which could not be reached if the conveyers were not susceptible of sidewise swing.

The power for driving side conveyers M and N is 10 derived, through an arrangement of sprockets and gears, from pulley F, which is caused to revolve by the passage of belt D over that pulley when the conveyer is in operation. Pulley F is rigidly keyed, or otherwise secured, on its shaft 1, and this shaft is 15 revolvably mounted in bearings. Rigidly secured on the end of shaft 1 is sprocket wheel 2, which is connected by sprocket chain 3 with sprocket wheel 4, rigidly secured on the outer end of shaft 5. This shaft is revolvably mounted in bearings, and has rigidly secured 20 on its inner end bevel gear wheel 6, which meshes with bevel gear 7, rigidly secured on the lower end of shaft 8. On the upper end of shaft 8 is rigidly secured bevel gear 9, which meshes with bevel gears 10 and 11, revolvably mounted on the inner ends of 25 their respective shafts 12 and 13.

The rotation of bevel gears 10 and 11 is transferred to their respective shafts when the outer members 14 and 15 of the spiral clutches 18 and 19 are thrown into engagement with their inner members 16 and 17. 30 Outer clutch members 14 and 15 are slidably mounted on their respective shafts, so that they may be thrown either into or out of engagement with the inner clutch members 18 and 19, and thus the transmission or non-transmission of power from shaft 8 to shafts 12 and 13 35 is controlled by the two clutches.

Rigidly secured on shafts 13 and 14 are two sprocket wheels numbered respectively 20 and 21. Sprocket 20 is connected by sprocket chain 22 with sprocket wheel 23, rigidly secured on shaft 24 of driving pulley 25 of 40 side conveyer M, and pulley 25 is rigidly secured on shaft 24 which is revolvably mounted in its bearings. In a similar manner the revolutions of shaft 13 is transferred to driving pulley 29 of side conveyer N by means of sprocket wheel 21, sprocket chain 26, sprocket 45 wheel 27, and shaft 28. The inner ends 28^a of the framing 29^a of side conveyers M and N are pivoted on the respective shafts 24 and 28, which permits of angular movement of the side conveyers in vertical planes, around those shafts. The bearings of shaft 24 50 are mounted on upper turntable 30, and the bearings of shaft 28 on lower turntable 31. These turntables turn around a common pivot, formed by hollow shaft 32, in which shaft 8 is supported. Lower turntable 31 forms a complete circle and is supported on plate 33, which rests on the lower timbers of the tripper frame. Upper turntable 30 is supported on lower turntable 31, and is cut away so that the two turntables may be 55 turned through a considerable arc around shaft 32 in opposite directions, without the supports and gears of the two side conveyers, which are mounted on the respective turntables, fouling each other. Thus provision is made for angular movement of the two side conveyers in a horizontal plane, around shaft 32. As

stated above, the movement of the side conveyers in both the horizontal and vertical planes is controlled by guys O, by means of turnbuckles P, or other similar devices.

The belts on side conveyers M and N travel in opposite directions, as indicated by the arrows, and discharge the material received from hopper G through 70 the respective chutes I and J, over the outer or head pulleys 34 and 35. As stated hereinbefore, the trajectories of the material discharged from the side conveyers, are susceptible of considerable variation by varying the height of the discharge ends of those conveyers. It is also possible by changing the relative sizes of the sprocket wheels or the gears, by means of 75 which power is transmitted from pulley F to the driving pulleys 25 and 29, to vary the speed of travel of the belts of the side conveyers, and thus to vary the 80 trajectories of the material discharged therefrom.

In the type of tripper shown in Fig. 6, a single side conveyer Q is rigidly supported on the lower timbers of the tripper, and on the opposite side of the tripper a counterweight R is similarly supported. The outer 85 ends of the conveyer and the counterweight are supported by guys S. This tripper has only one chute T, which discharges the material upon side conveyer Q. Power is transferred from upper bend pulley E to driving pulley 42 of side conveyer Q by means of sprocket 90 wheel 36, chain 37, sprocket 38, shaft 39, and bevel gears 40 and 41. The belt of the side conveyer travels in the direction of the arrow and discharges the material over head pulley 43.

In the form of tripper shown in Figs. 7 and 8, the hopper and chutes and the inner ends of the side conveyers X and Y are supported on the frame of tower U, which is rigidly connected with the tripper and travels on wheels V on track W. Guys Z, which support the outer ends of the side conveyers, are suspended from 95 the upper part of the tower frame. This arrangement of the tripper and traveling tower is designed for use with side conveyers which are so long as to require better support than can be given by the frame of the tripper itself. Furthermore, if the hopper and chutes, as 100 well as the side conveyers, are supported on the lower tower framing, the whole apparatus is better balanced, and the desirable object of removing much of the strain from the tripper itself is accomplished.

It will be seen that this invention contemplates a 110 conveying system provided with a main conveyer, a support, and an auxiliary or side conveyer, of which there may be more than one, movably connected with the support and having a gear wheel at said connection. Means are provided for elevating and again returning 115 the auxiliary conveyer to its normal position, and in order to drive the said auxiliary conveyer, a second gear wheel is provided, with gear wheels engaging said second wheel and the first gear wheel mentioned, at the connection between the auxiliary conveyer and the 120 frame. According to this construction, the main conveyer drives the auxiliary conveyer. The main conveyer it will be seen occupies a plane below that of the auxiliary conveyer whereon it discharges. Both the main and auxiliary conveyers are connected through 125 the interposition of bevel gear wheels, and it will be

seen that there are intermediate bevel gears meshing with said wheels whereby the auxiliary conveyer or conveyers are driven from the main conveyer, and at the same time provision is afforded for permitting the 5 free end of the auxiliary conveyer to be raised and lowered. The main conveyer it will be seen is mounted on a stationary structure but extends over and upon the tripper, while the auxiliary conveyer is mounted substantially at right angles to the main conveyer on 10 the tripper or traveling structure, and the auxiliary conveyer is driven by the main conveyer, as described.

According to this invention it will be seen that the cross auxiliary conveyer on the tripper is in a plane 15 above the main conveyer, while the tripper itself affords movable means for effecting the discharge of the material from the main conveyer upon the superimposed auxiliary conveyer. There is a power connection between the main conveyer and the tripper or movable discharging means, and it is obvious that the 20 tripper travels with the auxiliary conveyer and affords provision for elevating a portion of the main conveyer so that the material can be discharged therefrom upon the auxiliary conveyer. The tripper or deliverer constitutes a support, extending over or straddling the main 25 conveyer, said bridge or tripper carrying elevating devices over which the main conveyer travels. The auxiliary conveyer overlaps the main conveyer, and it will be seen that the auxiliary conveyer furthermore is in a plane above the major portion of the main conveyer, while the traveling deliverer or tripper is provided with an inclined portion over which a part of the 30 main conveyer passes.

Obviously, some features of this invention may be used without others, and the invention may be embodied in widely-varying forms.

Therefore, without limiting the invention to the con-

struction shown and described, nor enumerating equivalents, I claim and desire to obtain by Letters Patent the following:—

1. In a conveying system, the combination with traveling means for discharging material from the conveyer, of an auxiliary conveyer carried by said discharging means and having its free end movable in any direction, for substantially the purposes set forth. 40
2. In a conveying system, the combination with movable discharging means for the main conveyer, of an auxiliary conveyer carried by said movable discharging means and extending transversely to the general direction of the conveyer, the discharging end of said auxiliary conveyer being movable in any direction, for substantially the purposes set forth. 45
3. The combination with a tripper or deliverer for conveyers, of an auxiliary conveyer universally pivoted thereon, for substantially the purposes set forth. 50
4. The combination with a tripper or deliverer for a main conveyer, of an auxiliary conveyer universally pivoted thereon, and operative connections for driving the auxiliary conveyer from the main conveyer, for substantially the purposes set forth. 55
5. The combination with a tripper or deliverer for a main conveyer, of one or more auxiliary conveyers universally pivoted upon the deliverer and connected to be driven from the main conveyer, for substantially the purposes set forth. 60
6. The combination with a tripper or deliverer for conveyers, a plurality of auxiliary conveyers adjustably mounted thereon, and means for moving them in different directions. 65
7. The combination with a tripper or deliverer for conveyers, a plurality of auxiliary conveyers adjustably mounted thereon, both said auxiliary conveyers being constructed and adapted to simultaneously receive material from said deliverer and to convey it in different directions. 70

In testimony whereof I have signed this specification in the presence of two subscribing witnesses.

LINCOLN MOSS.
